Primary Examiner — Lauren D Mcvey*Assistant Examiner* — Mai Shim(74) Attorney, Agent, or Firm — Gloria Tsui-Yip; Gottlieb, Rackman & Reisman, P.C.(57) CLAIM

The ornamental design for a brush as shown and described.

DESCRIPTION

FIG. 1 is a top, right, and front perspective view of a brush showing our new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof;

FIG. 7 is a rear elevational view thereof; and,

FIG. 8 is a bottom, right, and front perspective view thereof. The broken lines immediately adjacent to the shaded areas depict the bounds of the claimed design, while all other broken lines are directed to environment. The broken lines form no part of the claimed design.

1 Claim, 6 Drawing Sheets(56)
